UNITED STATES PATENT OFFICE.

FREDERICK J. HEYBACH, OF SAVANNAH, GEORGIA.

AUTOMATIC TORCH LIGHTER.

Application filed October 15, 1926. Serial No. 141,823.

This invention relates to metal-cutting and welding apparatus, and particularly to oxyacetylene or other plural gas-burning torches.

5 One of the disadvantages attending the use of oxyacetylene torches as at present constructed is in the susceptibility of the flame to become extinguished frequently during the cutting or welding operation, necessitating 10 the relighting of the torch with matches and allowing the work to cool off in the meantime.

The present invention proposes the construction of a torch provided with automatic means for lighting and relighting it, which 15 means can instantly be brought into operative position and simultaneously actuated for lighting the torch, and which is automatically retracted after functioning, to a position entirely out of the way of the working 20 end of the torch and protected from the heat and sparks of the molten metal.

Another object of the invention is the provision of a torch, equipped with the lighting feature above described, having safety 25 means for automatically turning off the oxygen should the latter be on when the lighting device is operated, so that the acetylene alone will be available at the time of lighting.

Another object of the invention is to construct an oxyacetylene torch in which the gas controls as well as the lighting trigger are arranged within easy access of the fingers of the hand when grasping the handle of the 30 torch, so that all the controls incident to the operation of the torch shall be within convenient reach of the operator.

A further object of the invention is to provide a novel shield or housing for the lighting mechanism and the associated parts.

40 Other objects of the invention will appear as the following description of a preferred embodiment thereof proceeds.

In the drawings, in which similar reference characters are used throughout to denote 45 identical parts:—

Figure 1 is a view in side elevation of a torch embracing the principles of my invention;

Fig. 2 is a plan view of the same;

Fig. 3 is a side elevation on a slightly reduced scale, showing the casings in which certain of the parts are housed;

Fig. 4 is a longitudinal section through the lighting mechanism;

Fig. 5 is a longitudinal section of parts of

the lighting mechanism in condition of re-
pose;

Fig. 6 is a similar view, showing the parts in the biased position assumed when the lighter is actuated;

Fig. 7 is an underneath plan view of the casing which houses the lighting mechanism;

Fig. 8 is a side elevation of part of the torch, showing the obverse side to that shown in Fig. 3; and

Fig. 9 is a cross section taken along the line 9—9 of Fig. 7.

Referring now in detail to the several figures, the torch consists essentially of the acetylene pipe 1 and the oxygen pipe 2, both 70 of these pipes being brought together as usual into the single nozzle 3. At a convenient point, the pipes 1 and 2 pass through, and are made fast to, a handle 4.

A trigger 6 having a finger-piece 7 is pivotally mounted upon said torch adjacent said handle, for instance, at the point 8. The trigger oscillates when pressed, between limits indicated by the full and dotted lines in Fig. 1, and it reciprocates a link 9 which is 80 pivotally joined to and actuates the lighter 10.

The lighting mechanism consists of an arm 11 pivotally mounted upon a pin 10^a carried by a fixed U-shaped support 11^a. Said 85 arm carries at its end a magazine 12 of pyrophoric material, and adjacent the same in operative relation thereto, a disk 13 having a serrated edge 14. The disk, by preference, consists of a rim freely rotatable upon a central portion 15, constructed to expand when

biased in one direction so as to positively engage said rim, constituting a one-way clutch for imparting to the rim a step-by-step unidirectional rotation. The disk 13 is actuated 95 through an arm 14 pivotally associated with the clutch member 15 and normally biased in a direction to maintain said clutch expanded by means of springs 17 and 18, stretched between points on the respective arms 11 and 16. The arm 16 is caused to reciprocate relative to the arm 11 by means of a pawl 19 pivoted to the arm 11 and carrying a pin 20, which normally engages in a slot 21 in the arm 16.

When the link 9 is pushed by movement of the trigger 6 toward the working end of the torch, it oscillates the lighter from the full line position shown in Fig. 1 to the dotted line position. This causes the extremity 22 of 110

the pawl 19 to engage an abutment 23 formed on the torch, so as to swing said pawl about its pivot in a counter-clockwise direction as indicated by the arrow in Fig. 4. This causes 5 the pin 20 to bear against one side of the slot 21, thereby drawing the arm 16 in a direction opposed to the tension of the springs 17 and 18, permitting the one-way clutch to contract so that it partially rotates in a counter-clockwise direction relative to the rim of the disk 13, the latter being detained by frictional engagement with the pyrophoric substance. Finally, when the lighter reaches the dotted line position shown in Fig. 1, in which the 10 point of contact between the disk and pyrophoric substance at which the spark will take place is within operative distance of the jet of gas issuing from the nozzle 3, the pin 20 slips out of the notch 21, permitting the arm 16 to fly back under the tension of the springs 17 and 18, spreading the one-way clutch and causing it to bind against the rim of the disk 13 and giving it at the same time a partial rotation, which is transmitted to the rim, 15 rotating the latter against the pyrophoric material and creating a spark, which ignites the issuing jet of gas.

When the trigger is let go, the spring 24 restores the lighter to its normal position, 20 disengaging the pawl 19 from the abutment 23 so that said pawl, the arm 16 and the clutch parts affected thereby are restored to their normal position of repose ready for another act of ignition.

25 The acetylene and oxygen pipes are controlled respectively by the rotary valves 26 and 27, arranged adjacent the inner end of the torch. Since it is desired to control these valves remotely from these points, that is to say, at a point conveniently adjacent the handle 4, rack-bars 28 and 29 are provided, 30 engaging gears in the valves 26 and 27 and engaged respectively by thumb gears 30 and 31 mounted to rotate freely upon a stud 32, the latter being fixed to the torch. By turning either of the thumb gears manually, reciprocatory motion is transmitted to the associated rack-bar, which in turn rotates one of the gas-control valves. The ends of said rack-bars are preferably provided with adjustable 35 stops 33 and 34, limiting the movement of said rack-bars so that the flow of either or both of the gases may be precisely controlled.

The oxygen control valve is also automatically controlled by the trigger so as to ensure that the flow of oxygen will be shut off at the time the ignition spark is produced, leaving only the jet of acetylene to be ignited. In order to accomplish this automatic control, the trigger is provided with a lug 35 and the rack-bar 29 with a projection 36 which lies in the path of movement of the lug 35 in all positions of the rack-bar 29 when the oxygen valve is open.

60 In operation, the acetylene valve is first

opened to the desired degree by manual rotation of the thumb gear 30. The trigger is then pulled. If the oxygen valve is then open to any extent, the lug 35 on the trigger will collide with the projection 36 on the rack-bar 70 29, pushing the rack-bar back and closing the oxygen valve before the spark is made by the lighter. The oxygen valve is then opened by manual manipulation of the thumb gear 31. This of course throws the projection 36 75 again into the path of the lug 35 so that should the flame become extinguished and the trigger again have to be pulled, the oxygen valve will be again closed.

The igniter and its appurtenant mechanism 80 is preferably enclosed in a casing 40, suitably slotted at the top and bottom to permit the operation of the link 9 and the extension of the lighter 10. The moving parts within the casing are thus protected from damage incident to rough handling and from the heat and sparks of the molten metal. If desired the rack-bars may also be enclosed in a casing 41, as shown.

From the foregoing description it will appear that I have invented a self-lighting torch which automatically controls the flow of oxygen to the nozzle in such a way as to ensure that the said flow of oxygen will be cut off prior to the self-lighting of the torch. 95

It is to be understood that the details of construction with which I have described my invention are not to be considered as limitative in their effect upon the scope thereof, but merely by way of example, except where prescribed by the express terms of the appended claims.

What I claim as new is:

1. In a metal working torch, a flame nozzle, a lighter adjacent said nozzle, means for operating said lighter to move it to or from said nozzle, two pipes conveying, respectively, an inflammable and a non-inflammable gas to said nozzle, valves in said pipes, manually actuatable controlling means for said valves, the valve controlling the non-inflammable gas being responsive to control by said lighter operating means when open for closing said valve before igniting the inflammable gas at said torch. 110 115

2. In a metal working torch, a flame nozzle, a lighter adjacent said nozzle, means for moving said lighter into and out of operative relation to the nozzle, pipes conveying different gases to said nozzle, valves in said pipes, manually actuatable controlling means for said valves, and interengaging means associated with one of said valves and with said lighter moving means for closing said valve from any open position when the lighter moving means 120 125 is actuated.

3. In a metal working torch, a flame nozzle, a lighter adjacent said nozzle, means for operating said lighter, pipes conveying different gases to said nozzle, valves in said pipes, a 130

handle for said torch, manually actuatable controlling means for said valves adjacent said handle, rack bars connecting said controlling means and valves, and means on one of said 5 rack bars cooperating with said lighter operating means for closing the valve associated with said rack bar from any open position of the same when said operating means is actuated.

10 4. In a metal working torch, a flame nozzle, a lighter adjacent said nozzle, means for operating said lighter, pipes conveying different gases to said nozzle, valves in said pipes, a handle for said torch, manually actuatable 15 controlling means for said valves adjacent said handle, rack bars connecting said controlling means and valves, and means on one of said rack bars cooperating with said lighter operating means for closing the valve associated with said rack bar from any open position of the same when said operating means is actuated, said rack bars being provided with adjustable stops for limiting their movement in a valve-opening direction.

20 5. In a metal working torch, a nozzle, two pipes in communication with said nozzle, one of said pipes being adapted to convey an inflammable and the other a non-inflammable gas, two valves one mounted in each pipe, 25 a swingingly mounted frame relatively disposed to the nozzle, an automatic igniter carried by said frame, manually operated means for actuating the same, and means operably connecting the latter to the non-inflammable 30 gas control valve whereby said valve is automatically closed simultaneously with the energization of the lighter.

35

6. In a metal working torch, the combination of a hand-grip, two pipes mounted in said hand-grip, a nozzle in communication 40 with both of said pipes, two independent valves one mounted in each pipe, a lighting device adapted to be projected in the path of the nozzle, the latter being connected to the valve of the non-inflammable gas to cut 45 off said valve when in such projected position, and means for retracting the lighter.

7. In a metal working torch according to claim 6 in which the connection between the lighter and the valve consists of manually 50 operated means for opening and closing the valve, and automatic means associated with the latter and the automatic lighter for only closing the valve.

8. In a metal working torch, a hand-grip, 55 two pipes leading to said hand-grip and adapted to convey an inflammable and a non-inflammable gas respectively, a valve in each pipe, a nozzle connected to both of said pipes, a lever pivoted to the hand-grip, a pivoted 60 arm operably connected to the lever and adapted to have its free end move into and out of the path of the nozzle, a flame-forming member mounted in the free end thereof and adapted to be energized when in the path of 65 the nozzle, and means operably disposed in the path of the lever and connected to the valve for controlling the non-inflammable gas whereby said valve is closed when the 70 flame-forming member is projected and in the path of the nozzle.

In testimony whereof I have hereunto set my hand.

FREDERICK J. HEYBACH.
